US00D598019S

(12) **United States Design Patent**
Chou

(10) **Patent No.:** **US D598,019 S**
(45) **Date of Patent:** **** Aug. 11, 2009**

(54) **DATA STORAGE AND BACKUP APPARATUS
OF COMPUTER AND ELECTRONIC SYSTEM**

(75) Inventor: **Wei-Min Chou**, Taipei County (TW)

(73) Assignee: **Accusys Inc.**, Hsinchu (TW)

(**) Term: **14 Years**

(21) Appl. No.: **29/318,606**

(22) Filed: **May 22, 2008**

(51) **LOC (9) Cl.** **14-02**

(52) **U.S. Cl.** **D14/356**

(58) **Field of Classification Search** **D14/125, D14/137, 167–168, 230–231, 233, 235, 237, D14/240–242, 299, 432, 435–436, 155, 496, D14/300–301, 313–314, 214, 348–349, 351–363, D14/365–370; D18/56; D10/65, 75, 78; D13/149, 162, 184, 199; D3/201, 273; 312/223.1, 312/223.2; 369/34.01, 36.01, 272.1; 360/132, 360/133, 135; 361/685–686; 379/93.01; 720/613; 711/15, 100, 115**

(57) **CLAIM**

The ornamental design for data storage and backup apparatus of computer and electronic system, as shown and described.

DESCRIPTION

FIG. 1 is a perspective view of data storage and backup apparatus of computer and electronic system.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view of data storage and backup apparatus of computer and electronic system; and,

FIG. 7 is a bottom plan view thereof.

The broken lines shown in FIG. 7 are included for the purpose of illustrating unclaimed portions of the design and form no part of the claimed design.
